UNITED STATES PATENT OFFICE.

JAMES D. JOYCE, OF PHILADELPHIA, PENNSYLVANIA.

WINDING MACHINE.

Application filed January 25, 1924. Serial No. 688,592.

To all whom it may concern:

Be it known that I, JAMES D. JOYCE, a citizen of the United States, residing at Philadelphia, in the county of Philadelphia and State of Pennsylvania, have invented certain new and useful Improvements in Winding Machines, of which the following is a specification.

This invention relates in general to winding machines, and more particularly to a winding machine having means for simultaneously winding a plurality of bobbins, each of which is separately and automatically controlled.

15 It is an object of my invention to provide a novel and improved bunch building means for winding machines of this type.

It is a further object of my invention to provide a novel and improved control mechanism for winding machines such that if the thread or yarn being wound breaks, the spindle of that bobbin will be automatically thrown out of action. Means is also provided for automatically throwing the spindle 25 out of operation when the same is completely wound.

It is an object of my invention to provide a novel type of brake means, automatically operating to stop the rotation of the spindle 30 when the same is thrown out of action.

It is a further object of my invention to provide a novel type of travelling thread guide carrier, the follower of which can rotate in but one direction and thus provides 35 against any back lash of the carrier.

Other objects and advantages of my invention will appear in the accompanying specification and claims and will be disclosed in the accompanying drawings in which—

40 Figure 1 is a plan view of a portion of my device showing one of my opposed winding devices and a portion of my power transmission system;

Figure 2 is a vertical section through the 45 transmission housing;

Figure 3 is an enlarged end elevation, partly in section, and with portions broken away, of one of my spindle operating means;

50 Figure 4 is an end elevation, partly in section, and with portions broken away, showing the complete operating mechanism for one of my spindles;

Figure 5 is an enlarged vertical detail view, largely in section of a portion of the 55 device as shown in Figure 4;

Figure 6 is a plan view of my bunch building mechanism;

Figure 7 is a perspective of my bunch builder;

Figure 8 is an end view of my bunch builder, largely in a section taken on the line 8—8 of Figure 6;

Figure 9 is an end view largely in a section taken on line 9—9 of Figure 7;

Figure 10 is an enlarged end view, partly 65 in section, of my automatic clutch throw out mechanism;

Figure 11 is an end view of a portion of my travelling thread guide carrier;

Figure 12 is a diametrical section of the 70 device shown in Figure 11;

Figure 13 is a showing of a bobbin wound by a winding machine of the type disclosed in the preceding figures;

Figure 14 is an end elevation of a modification of my device;

Figure 15 is a showing of a bobbin wound by an apparatus of the type shown in Figure 13;

Figure 16 is a view similar to that shown 80 in Figure 5 showing a modification of my device;

Figure 17 is a view similar to Figure 10 showing a modification of my device;

Figure 18 is a detail view of the arm acted 85 on by the thread guide to throw out the clutch when the bobbin is full.

Referring with greater particularity to the drawings, and, for the first portion of this specification, having reference especially to 90 Figures 1—13, inclusive, it will be seen that my device is comprised as follows:

My machine is adapted to drive a plurality of spindles arranged in two longitudinally extending banks or rows. Each spindle in 95 each bank is each mounted opposed to a spindle of the other bank so that the two spindles are adapted to be operated by a common operating means. Since the construction of each of the spindle operating 100 means is substantially identical, the description is limited largely to the description of but one of such means.

Referring first to Figures 1 and 2, it will be seen that the power for the operation of 105 my winding machine derived from any suitable source is applied through a drive shaft 1.

One end of the drive shaft 1 extends into a transmission housing 1^a and has suitable bearings 1^b. Mounted on the end of shaft 1 110

is a pinion gear 2, adapted to mesh with and drive a bevel gear 3 secured to a stub shaft 4 mounted in suitable bearings in the housing. Fixedly secured to shaft 4 is a cam block 5 having a cam track 5^a in which a pair of oppositely spaced rollers 6 secured to rock arms 7 are adapted to travel. The rotation of shaft 4 will thus result in the oscillation of the rock arms 7 and hence of the rock shafts 8 on which the said arms are mounted. The rocking of shafts 8, as will be later described, provides for the traversing movement of the thread guide and many of the other of the moving parts of my device.

Fixedly mounted on shaft 1 are a plurality of friction wheels 9, each adapted at its periphery to drive a pair of friction disks 10, mounted on shafts 11 to rotate therewith but slidable thereon, which shafts carry the spindles on which the bobbins 12 are to be wound. The thread or yarn 13 passes through either of two thread guides 14^a or 14^b, the guide 14^a being used when the thread is fed from below the spindle and the guide 14^b being used when the thread is fed from above. (See Figures 1 and 10). The thread then passes through the travelling thread guide 15 and over a bent pin 16 on the bunch building device.

Reference being had especially to Figures 1 and 3, it will be seen that a clutch 17, which can be thrown into or out of operation by a handle 18, is mounted on the shaft 8. This clutch is also capable of automatic control, as will be disclosed in the following specification.

Mounted on a collar 20^a on shaft 8 is a substantially vertically extending rod 20 to which there is pivoted at 21 a bar 22, which bar is reciprocated longitudinally of the spindle by the oscillation of the shaft 8. The bar 22 has secured thereto the bars 23 and 24 which carry one end of the rod 25, along which the travelling thread guide moves, and the shaper rod 26. The collar 20^a is adapted to be engaged by the clutch 17 through the means of a pin 17^a adapted to be moved into or out of a slot 20^b in the collar 20^a as the clutch is moved longitudinally of the shaft.

Referring now especially to Figures 1, 6, 7, 8 and 10, it will be seen that the bent pin 16 is mounted on an arm 30, pivoted at 31 to a member 32, which in turn is pivoted to the frame of the machine. The end of the arm 30 lies against the under face of the few turns of thread which are manually wound on the bobbin as it is placed in position. As the spindle is put into operation the thread is restrained from the traversing movement of the guide 15 by the bent pin 16. As the bunch is being built, the end 34 of the arm 30 will be gradually pushed downwardly about the pivot 33 un-

til the inner end 35 of the arm 30 is in registration with a slot 36 in a plate 37 secured to the frame. The spring 38 will then cause the arm 30 to rotate about pivot 31, causing the bent end of the pin 16 to move out of engagement with the thread, and the winding proceeds, the thread now being reciprocated along the bobbin by the guide 15.

The thread guide 14^a is secured by means of a collar 40 to a rod 41. On the inner end of rod 41 there is fixedly mounted a curved arm 42 carrying pins 43 between which passes the arm 44 which carries the thread guide carrier 14^b. If the thread guide 14^a is being used and the thread breaks, the arm carrying 14^a will drop, rotating the shaft 41, arm 42, and by means of pins 43 draws down on arm 44 rotating the collar 44^a on the stud 45 to which collar arm 44 is secured. The collar 44^a also carries a finger 46 which rotates with it. If the thread is carried by guide 14^b the arm 44 will fall when the thread breaks thus rotating the collar 44^a and finger 46.

Mounted on rod 24 is a collar 47 (see Fig. 3) which reciprocates therewith. A stub shaft 48 mounted in the frame of the machine carries a finger 49 and a collar 50. Mounted on the handle 18 is a finger 51 bearing against the periphery of collar 50 and holding the clutch in engagement against the tension of a spring 52. The collar 47, at the end of the outward stroke of the rod 24, does not quite reach the finger 49. If the thread breaks, however, the thread guides drop raising the finger 46 into the path of the collar 47. Then, as the rod 24 nears the outward end of its stroke, the collar 47 will strike the finger 46 which in turn strikes the finger 49 moving the shaft 48 longitudinally and moving the collar 50 out of engagement with the finger 51.

The spring 52 will then cause the handle 18 to turn through a partial revolution, and through the medium of the arm 55 and the pin 56, will throw the clutch out of engagement, the pin 56 riding in a groove in the clutch.

Pivoted on a pin 60, which is secured to the frame, is a lever 61, to the outer end of which there is secured the spring 52. At the opposite end of the lever 61 is a brake 62, so mounted that, when the spindle is thrown out of action, the brake 62 will strike the disk 10 pushing it away from the drive wheel 9 and stopping the same.

The lever 61 carries a hooked finger 64 which is in engagement with a pin 65 on a cam member 66 rotatably mounted on shaft 11. The cam member 66 is adapted to co-act with a cam 71 fixed on the shaft 11. When the clutch is thrown in, the lever 61 is raised by a pin 68 secured on an arm 69 mounted on the handle rod 18. This releases the pull on 65, and by means of the pull of a weight

70, and the gradual pull of light springs 77 the cam member 66 will be rotated bringing the highest portion of its cam surface into engagement with the highest portion of the cam surface of the member 71, and thus moving the disk 10 into engagement with the wheel 9 which drives the spindle, the clutch 66 and disk 10 being secured together. It is to be noted that the clutch is moved 10 longitudinally of the shaft 8 in such a manner that, when the clutch is thrown out the pin 17^a is withdrawn from its groove in the collar 20^a and the oscillatory motion of rod 20 is stopped.

15 When the spindle is fully wound the arm 75 of the thread guide carrier assembly will engage the finger 76 mounted on the shaft 41, thus partially rotating the shaft 41 and, through the medium of arms 42 and 44 will 20 raise the finger 46 into the path of the collar 47 and throwing the spindle out of operation.

In Figure 16 I have shown a modification of my invention in which I have replaced 25 the cam, weight and spring clutch mechanism, 64, 65, 66, 70, 77, by a compression spring 81 mounted on shaft 11 between the frame and the disk 10. This spring is of less strength than the spring 52 so that when 30 handle 18 is rotated to throw the spindle out of action the spring 52 acting on one end of the lever 61 will force the brake 62 against the disk 10 and force the same, against the action of spring 81, out of engagement with the wheel 9. When the spindle is again to be placed in operation the rotation of the handle 18 withdraws the brake from the disk and the spring 81 forces the disk into engagement with the wheel.

40 In Figure 17 I have disclosed a modification of the mechanism shown in detail in Figure 11, especially parts 14^b, 42, 43, 44, 45 and 46. In this showing I have done away with the curved arm 42, pins 43, and stud 45 and have shown the finger 46 as twisted and secured directly to the shaft 41, to which the arm of carrier 14^b is directly secured by means of a suitable collar.

Referring now especially to Figure 6 it 50 will be seen that the rods 23 and 24 are secured to each other by plate 28, the arm 23 being extended at 27 to form a support for the shaper 26 fixedly secured thereto.

The plate 28 has a longitudinally extending slot 28' in which a pin supporting one end of the rod 25 is adapted to travel. The other end of rod 25 is pivoted at 82 to a plate 83.

By reference to Figure 9 it will be seen 60 that I have provided a spring 84 one end of which is attached to a finger extending from the rod 23 and the other of which is secured to a finger extending from the rod 25. This spring tends to bring rod 25 into alignment with the rod 24. A suitable friction collar 85 is provided with spring 86 abutting a

collar 86^a and is adapted to bear against the edge of plate 28.

A finger 87 has an undercut portion 88 adapted to bear on the edge of the shaper, the finger being mounted on a portion of 70 the traveling carrier of thread guide 15. The finger 87 moving along the shaper keeps the rod 25 out of alignment with rod 24 during the first part of the winding and which causes the yarn to be wound on the 75 bobbin as is shown in Figure 13.

The thread guide carrier consists of a forked member 90, on which the guide 15 is secured. The two arms of the forked members are secured to collars 91 and 92 which 80 are mounted on a sleeve 93 on rod 25. The sleeve 93 has secured thereto, by means of a collar 94, a follower wheel 95 the periphery of which is adapted to touch the yarn on the bobbin as it is wound and thus rotate 85 the wheel. Pivoted to the wheel 95 at 96 is a bent arm or yoke 97 which is shaped as shown in Figure 11 to provide a housing for a worm gear 98 and bearings for the shaft 99 on which the said worm is mounted. The 90 gear 98 extends through a recess 98' in the sleeve 93 and engages the threaded rod 25 with which it is held in engagement by a spring 100. The rotation of the wheel thus results in the whole thread guide assembly 95 being moved along the rod 24.

A spiral spring 102 is wrapped tightly around the extended arm of the shaft 99 in the manner shown in Figure 11. The inner end of the spring is held in position by 100 yoke 97. While the worm 98 can be rotated in a counterclockwise rotation (as viewed in Figure 12) it will be seen that any attempt to rotate the worm in the opposite direction would cause the spring 102 to bind 105 the shaft 98 and prevent rotation. To move the thread guide backwards then, it is necessary to raise the yoke 98 about its pivots against the action of spring 100. The carrier can then be moved back to any desired 110 position, the sleeve 93 now sliding freely on the rod 24.

In the device shown in Figure 14 I have dispensed with the double rod 23, 24, 25, 27 and have substituted a single rod 25. The 115 shaper is naturally dispensed with and the bobbin wound is, when completed, as shown in Figure 15.

The operation of my device having been 120 fully disclosed, it will be seen that I have provided a winding machine for simultaneously winding a plurality of bobbins, each bobbin being independently and automatically controlled in its winding, having novel means for automatically throwing a bobbin 125 into or out of operation when the thread feeding it breaks or when the bobbin is fully wound; which has a novel and improved type of bunch builder; and which is simple in construction and operation. 130

I claim:

1. In combination, in a winding machine, a frame, a plurality of spindles rotatably mounted in said frame, means for rotating said spindles, a traversing thread guide for each spindle, means for traversing said thread guides longitudinally of said spindles, and means manually operable to throw any of said spindles and its traversing thread guide simultaneously out of operation while permitting the operation of the remainder of said spindles.

2. In combination, in a winding machine, a frame, a plurality of spindles rotatably mounted in said frame, means for rotating said spindles, a traversing thread guide for each spindle, means for traversing said thread guides longitudinally of said spindles, and means automatically operable through said traversing means to throw any of said spindles and its traversing thread guide simultaneously out of operation when the thread being fed to said spindle breaks.

3. In combination, in a winding machine, a frame, a plurality of spindles rotatably mounted in said frame, means for rotating said spindles, a traversing thread guide for each spindle, means for traversing said thread guides longitudinally of said spindles, means automatically operable through said traversing means to throw any of said spindles and its traversing thread guide simultaneously out of operation when the thread being fed to said spindle breaks, and means for braking said spindle.

4. In combination, in a winding machine, a frame, a plurality of spindles rotatably mounted in said frame, means for rotating said spindles, a traversing thread guide for each spindle, means for traversing said thread guides longitudinally of said spindles, and means automatically operable through said traversing means to throw any of said spindles and its traversing thread guide simultaneously out of operation when the thread being fed to said spindle breaks or when the bobbin on said spindle is fully wound.

5. In combination, in a winding machine, a frame, a plurality of spindles rotatably mounted in said frame, means for rotating said spindles, a traversing thread guide for each spindle, means for traversing said thread guides longitudinally of said spindles, means automatically operable through said traversing means to throw any of said spindles and its traversing thread guide simultaneously out of operation when the thread being fed to said spindle breaks or when the bobbin on said spindle is fully wound, and means for braking said spindle.

6. In combination, in a winding machine, a frame, a plurality of spindles secured on spindle shafts rotatably mounted in said

frame, a traversing thread guide for each spindle, reciprocating means for traversing said thread guide, a power shaft having a plurality of drive wheels mounted thereon, friction disk fixed on said spindle shafts 70 adapted to engage said drive wheels to rotate said spindle shaft, and means adapted to be moved into the path of said reciprocating means to automatically throw any of said friction disks out of operative connection with its driving wheel when the thread being fed to that spindle is broken or when the bobbin on the said spindle is fully wound.

7. In combination, in a winding machine, a frame, a plurality of spindles secured on spindle shaft rotatably mounted in said frame, a traversing thread guide for each spindle, reciprocating means for traversing said thread guide, a power shaft having a plurality of drive wheels mounted thereon, friction disk fixed on said spindle shafts adapted to engage said drive wheels to rotate said spindle shaft, means adapted to be moved into the path of said reciprocating means to automatically throw any of said friction disks out of operative connection with its driving wheel when the thread being fed to that spindle is broken or when the bobbin on the said spindle is fully wound, and means for automatically braking said friction disk.

8. In combination, in a winding machine, a frame, a spindle rotatably mounted in said frame, a bobbin on said spindle, a traversing thread guide for said spindle adapted to traverse the thread longitudinally thereof, restraining means adapted to engage the thread to limit the traversing movements, and supporting means carrying said restraining means and adapted to move the same out of engagement with said thread when a bunch of predetermined thickness has been wound, said supporting means having an arm thereof adapted to bear against the thread on the bobbin during the bunch building operation to move said supporting means in accordance with the thickness of the bunch being built.

9. In combination, in a bunch builder for a winding machine having a traversing thread guide adapted to be reciprocated longitudinally of the spindle of said winding machine, an arm capable of pivotal movement about both vertical and horizontal pivots, restraining means on said arm adapted to engage the thread being fed from the thread guide to a bobbin on the said spindle and adapted to limit the traversing movement of said thread during the bunch building operation, said arm having a portion thereof adapted to bear against the yarn in said bunch to move said arm about its horizontal pivot, and resilient means adapted to move said arm about its vertical pivot 120 125 130

when the bunch has reached a predetermined thickness.

10. In combination, in a winding machine, a frame, a plurality of spindles secured on 5 spindle shafts rotatably mounted in said frame, a traversing thread guide for each spindle, reciprocating means for traversing said thread guide, a power shaft having a plurality of drive wheels mounted thereon, 10 friction disk fixed on said spindle shafts adapted to engage said drive wheels to rotate said spindle shaft, means adapted to be moved into the path of said reciprocating means to automatically throw any of said 15 friction disks out of operative connection with its driving wheel when the thread being fed to that spindle is broken or when the bobbin on the said spindle is fully wound, and means for simultaneously throwing 20 said reciprocating means out of operation.

11. In combination, in a winding machine, a frame, a plurality of spindles secured on spindle shaft rotatably mounted in said 25 frame, a traversing thread guide for each spindle, reciprocating means for traversing said thread guide, a power shaft having a plurality of drive wheels mounted thereon, friction disk fixed on said spindle shafts 30 adapted to engage said drive wheels to rotate said spindle shaft, means adapted to be moved into the path of said reciprocating means to automatically throw any of said 35 friction disks out of operative connection with its driving wheel when the thread being fed to that spindle is broken or when the bobbin on the said spindle is fully wound, and means for automatically braking 40 said friction disk, and means for simultaneously throwing said reciprocating means out of operation.

12. In a traverse mechanism for a winding machine, the combination with a reciprocating guide, a traverse arm and means 45 connecting the two, and a rock shaft to oscillate said arm, of means to shift the arm on the shaft to disconnect it from oscillatory engagement.

13. In combination, in a winding machine, 50 a frame, a plurality of spindles secured on spindle shaft rotatably mounted in said frame, a traversing thread guide for each spindle, reciprocating means for traversing said thread guide, a power shaft having a plurality of drive wheels mounted thereon, 55 friction disk fixed on said spindle shafts adapted to engage said drive wheels to rotate said spindle shaft, a rod rotatably mounted in said frame parallel to said spindle, an

arm on said rod adapted to be moved into 60 the path of said reciprocating means to automatically throw any of said friction disks out of operative connection with its driving wheel when the thread being fed to that spindle is broken or when the bobbin on the 65 said spindle is fully wound, and means for automatically braking said friction disk.

14. In combination, in a winding machine, a frame, a plurality of spindles secured on said spindle shaft rotatably mounted in said 70 frame, a traversing thread guide for each spindle, reciprocating means for traversing said thread guide, a power shaft having a plurality of drive wheels mounted thereon, friction disk fixed on said spindle shafts 75 adapted to engage said drive wheels to rotate said spindle shaft, a rod rotatably mounted in said frame parallel to said spindle, means to rotate said rod when the bobbin is fully wound or when the thread 80 breaks, an arm on said rod adapted to be moved by the rotation of said rod into the path of said reciprocating means to automatically throw any of said friction disks out of operative connection with its driving 85 wheel when the thread being fed to that spindle is broken or when the bobbin on the said spindle is fully wound, and means for automatically braking said friction disk.

15. In combination, in a winding machine, 90 a frame, a spindle rotatably mounted in said frame, a traversing thread guide for each spindle, reciprocating means for traversing said thread guide, a stop mechanism for said traversing thread guide, a collar on said reciprocating means which in the travel of the reciprocating means stops short of the stop 95 mechanism, and means automatically movable into the path of said collar to cause the same to operate said stop mechanism when 100 the thread breaks or when the bobbin is fully wound.

16. In combination, in a winding machine, a frame, a spindle rotatably mounted in said frame, means for rotating said spindle, a 105 traversing thread guide for each spindle, reciprocating means for traversing said thread guide, a stop mechanism for said traversing thread guide and said spindle, a 110 collar on said reciprocating means which in the travel of the reciprocating means stops short of the stop mechanism, and means automatically movable into the path of said collar to cause the same to operate said stop mechanism when the thread breaks or when 115 the bobbin is fully wound.

In testimony whereof I affix my signature.
JAMES D. JOYCE.
